UNITED STATES PATENT OFFICE

132,176

DESIGN FOR AN ELECTRICALLY HEATED WATER BATH

Samuel Duberstein, Brooklyn, N. Y., assignor to
American Sundries Company, Inc., a corpora-
tion of New York

Application May 22, 1941, Serial No. 101,183

Term of patent 7 years

To all whom it may concern:

Be it known that I, Samuel Duberstein, a citizen of the United States of America, residing at Brooklyn, in the county of Kings and State of New York, have invented a new, original, and ornamental Design for an Electrically Heated Water Bath, of which the following is a specification, reference being had to the accompanying drawing, forming a part thereof.

Fig. 1 is a perspective view of an electrically

heated water bath showing my new design, and
Fig. 2 is a side elevational view thereof.

The design of the side of the electrically heated water bath opposite to the side shown in Fig. 2 is substantially similar thereto.

I claim:

The ornamental design for an electrically heated water bath, substantially as shown and described.

SAMUEL DUBERSTEIN.
